CLAIM

The ornamental design for a combined corkscrew and can opener or similar article, substantially as shown.

DESCRIPTION

FIG. 1 is a side elevational view of a combined corkscrew and can opener or similar article showing my new design;

FIG. 2 is a side elevational view thereof as seen from the right hand portion of FIG. 1;

FIG. 3 is a side elevational view thereof showing the side opposite that seen in FIG. 1;

FIG. 4 is a side elevational view thereof showing the side opposite that seen in FIG. 2;

FIG. 5 is a bottom plan view thereof; and

FIG. 6 is a top plan view thereof.

FIG. 1

FIG. 2

FIG. 3

FIG. 4

FIG. 5

FIG. 6
